ASPIRATOR AND METHOD OF MAKING THE SAME

William E. Whitney, Cambridge, Mass., assignor, by mesne assignments, to Stator Corporation, a corporation of Rhode Island

Application November 25, 1939, Serial No. 306,058

4 Claims. (Cl. 230—95)

This invention relates to improved aspirator mixing chambers and to a method of making a preferred form of mixing chamber.

When aspirators are employed in permanently sealed systems which should maintain operating efficiency for a long period of time without requiring attention, it is highly desirable to construct the aspirator or aspirators so that leakage through the walls thereof is avoided. For example, in the case of refrigerating systems such as disclosed in the copending application of Lyman F. Whitney, Serial No. 177,749, filed December 2, 1937, it is desirable to arrange all parts of the system, including the aspirator mixing chambers, so that leakage of atmospheric air into the system is practically precluded. Systems of this character may operate at relatively low pressures; for example, pressures of only a few millimeters of mercury absolute may prevail in the aspirator heads. The leakage of air into such a system, even at a slow rate, might seriously impair operating efficiency.

In general, the parts of the system are constructed of elements such as steel tubing, which may be welded together substantially to preclude inward leakage of atmospheric air. I have discovered, however, that conventional forged or cast aspirator mixing chambers, although practically impervious to the passage of gas, will, over a relatively long period of time, permit the slow leakage of gas into a system of the present type. I have found that such leakage apparently may be due to the disposition of the metal grain and particularly to the existence of minute channels or flow lines in the metal extending through the walls of the head.

In the preferred embodiment of the invention, I provide a forging formed of an original plate or metal part, with the metal grain so disposed both in the original metal part and in the ultimate forging that even slight leakage through the latter is substantially precluded when the forging is assembled with cooperating parts to afford an aspirator mixing chamber. Furthermore, a forging of this type may afford an advantageous shape for the mixing chamber to facilitate relatively high operating efficiency.

I have also found that a similar result may be attained, in so far as leakage is concerned, by building up an aspirator mixing chamber out of plate-sections, a ring section and the like, each section having the metal grain thereof disposed in a general manner corresponding to that of the metal grain in the forged mixing chamber. In any case, I have found it advantageous to

arrange the outer wall of the mixing chamber as well as the end wall thereof so that the metal grain extends substantially in the plane of the corresponding wall portion rather than extending transversely of the same. Such an arrangement avoids the slight porosity that otherwise would be likely to be present in the aspirator mixing chamber and which might ultimately result in the leakage of an appreciable quantity of gas into the sealed system.

In the accompanying drawings,

Fig. 1 is a central vertical section of a mixing chamber and adjoining parts, showing such a mixing chamber constructed in accordance with the present invention;

Fig. 2 is a similar view of an optional form of mixing chamber and adjoining parts;

Fig. 3 is an isometric part of a metal plate which may be employed to make the body of the mixing chamber shown in Fig. 1;

Figs. 4 and 5 are sectional views on planes at right angles to each other and showing an intermediate forging formed of the metal plate shown in Fig. 3; and

Fig. 6 shows the final form of the forging made from the plate of Fig. 3.

Fig. 1 shows the mixing chamber and adjoining parts of an aspirator of the general type disclosed in the above-mentioned application of Lyman F. Whitney. Such an aspirator is provided, for example, with a propellant supply tube 1 from which propellant vapor, such as mercury vapor, passes through an aspirator nozzle 2 into a mixing chamber, designated generally by the numeral 3. A bracket, designated by numeral 4, holds the nozzle 2 in alignment with an aspirator funnel 6, the latter being surrounded by cooling fins 7 disposed within a jacket 8. The mixing chamber may comprise a domed head 10 of relatively thin metal, this head being formed by dishing a plate in such a manner that the metal grain in each section of the head lies substantially in the plane of that section. The nozzle 2 extends through the head. The remainder of

the mixing chamber may be provided by a forging 14 providing an outer annular wall 15 and an inner end wall 16 into which the end of the tubular aspirator funnel fits in alignment with nozzle 2. The head 10 is welded to the annular wall 15. The forging 14 also provides an annular flange 18 which is provided with a rabbet to receive the end of the jacket member or sleeve 8.

In accordance with the present invention, the forging is preferably provided with the metal grain in each part thereof preponderantly ex-

tending in the direction of the inner surface of the corresponding section of the wall rather than transversely of the same. Thus the forging as well as the dished head 10 may be substantially free of flow lines or minute passages extending transversely to adjoining inner surfaces of the chamber. Thus Fig. 6 shows the forging 14 before the same has been assembled with the other parts of the aspirator, the position of the light lines indicating the preponderant direction of the metal grain. It will be noted that the intermediate part of the wall 16 is provided with an inwardly tapered surface to be disposed about the end of the funnel 6. The inner surface of the outer wall of the forging is preferably machined before assembly with the rest of the mixing chamber. This general form of forging I have found particularly conducive to aspirating efficiency while also entirely consistent with good forging practice.

Figs. 3 to 6 indicate how a forging of the type shown in Fig. 1 may be formed with its metal grain or flow lines so disposed as to avoid the slight porosity characterizing ordinary forgings, which might be objectionable in sealed apparatus of the character referred to herein. The forging may be formed from a flat plate or piece of stock 20 which has been so prepared by rolling or otherwise that the direction of its metal grain is substantially parallel to its planar surfaces. Such a plate may be heated and then hot pressed between suitable dies to give a cup-like form, such as shown in Figs. 4 and 5, which are sections at right angles to each other. The light lines in Fig. 4 show the direction of the flow lines or metal grain, while in Fig. 5 the light dots show how the metal grain is cut by this sectional view. A final hot forging operation with suitable dies may then be effective in forming the member 14 which is shown in Fig. 6, it being evident that the metal grain in the central portion of the forging extends parallel to the upper surface of this part of the forging as viewed in Fig. 6, that the grain of the beveled surface surrounding this central portion is correspondingly parallel to such beveled surface, and that the grain in the outer annular wall is substantially parallel to the inner surface of that wall. At the outer part of the forging and at the part thereof which is to receive the jacket sleeve 8, the metal grain may extend in the directions shown in Fig. 6, these portions of the forging not being important in so far as leakage from the mixing chamber is concerned.

Some of the advantages of the arrangement shown in Fig. 1 can also be obtained with an assembly of the type shown in Fig. 2. This assembly comprises a propellant supply duct 1, a nozzle 2, and a bracket 4 similar to those previously described. A head 110, corresponding to the head 10, is also provided for the mixing chamber 103. The outer wall of this chamber is, however, afforded by a small ring section 115 with the grain of the metal extending parallel to the inner surface portions of the corresponding parts of the ring. Such a ring may conveniently be provided by cutting a short section from a tube, it being well recognized that tubular stock generally has its metal grain extending parallel to the longitudinal axis of the tube. The inner wall 116 of the head may be formed of a plate having its metal grain parallel to its planar surfaces. The plate is cut to provide a disk that may be welded to the member 115, the latter in turn being welded to the head 110. A

second ring section 118 may be welded to the disk 103 to provide a member for connection to the jacket sleeve of the aspirator.

It will of course be understood that the annular outer wall of the mixing chamber shown in Fig. 1 or the corresponding wall of the chamber shown in Fig. 2 may be cut away as by a drill to afford a suitable opening and a vapor supply pipe may be welded to the wall about this opening to permit the flow of vapor, such as refrigerant vapor, into the mixing chamber. For example, the detailed structural arrangement of the connection of the vapor duct to the outer wall of the mixing chamber is shown in the above-identified Whitney application.

In general, an aspirator head formed as shown in Fig. 2 approximates the resistance to leakage that is permitted by a head of the type shown in Fig. 1. I, however, prefer a head such as shown in Fig. 1 formed from a forging wherein the metal particles have been compacted under heat and pressure. Furthermore, such a member may readily be shaped to facilitate high aspirating efficiency.

It should be understood that the present disclosure is for the purpose of illustration only and that this invention includes all modifications and equivalents which fall within the scope of the appended claims.

30 I claim:

1. An aspirator comprising a nozzle, a funnel aligned with the nozzle, a mixing chamber between the funnel and nozzle and connected thereto, said mixing chamber having a head through which the nozzle may supply propellant vapor, said mixing chamber also having an inner end wall and an outer annular wall both provided by a single forging, the inner end wall providing a central opening where the funnel is connected thereto and being beveled about said opening, the forging being characterized by metal-grain structure preponderantly paralleling the inner surfaces of adjoining wall portions, and being substantially free of pores and flow lines extending transversely to said surfaces.

2. An aspirator comprising a nozzle, a funnel aligned with the nozzle, a mixing chamber between the funnel and nozzle and connected thereto, said mixing chamber having a head through which the nozzle may supply propellant vapor, said mixing chamber also having an inner end wall and an outer annular wall both provided by a single forging, the inner end wall providing an opening where the funnel is connected thereto, the forging being characterized by metal grain structure which preponderantly parallels the inner surfaces of adjoining wall portions and which is substantially free of pores and flow lines extending transversely to said surfaces.

3. An aspirator comprising a nozzle, a funnel aligned with the nozzle, a mixing chamber between the funnel and nozzle and connected thereto, said mixing chamber having a head through which the nozzle may supply propellant vapor, said mixing chamber also having an inner end wall and an outer annular metal wall, the inner end wall providing an opening where the funnel is connected thereto, the metal of the outer wall being characterized by grain structure which preponderantly parallels the inner surfaces of adjoining portions of said outer wall and which is substantially free of pores and flow lines extending transversely to said surfaces.

4. An aspirator comprising a nozzle, a funnel

aligned with the nozzle, a mixing chamber between the funnel and nozzle and connected thereto, said mixing chamber having a head through which the nozzle may supply propellant vapor, said mixing chamber also having a metal inner end wall and an outer annular wall between the head and the inner wall, said inner end wall providing an opening where the funnel

is connected thereto, the metal of said inner wall being characterized by metal grain structure which preponderantly parallels the inner surfaces of adjoining portions of said inner wall and which is substantially free of pores and flow lines extending transversely to said surfaces.

WILLIAM E. WHITNEY.
